UNITED STATES PATENT OFFICE.

EDWARD T. REDDING, OF SWISSVALE, PENNSYLVANIA, ASSIGNOR TO CONSOLIDATED EXPANDED METAL COMPANY, A CORPORATION OF PENNSYLVANIA.

APPARATUS FOR MAKING FLATTENED EXPANDED-METAL REINFORCEMENT.

1,370,361.

Specification of Letters Patent.

Patented Mar. 1, 1921.

Application filed September 9, 1918. Serial No. 253,149.

To all whom it may concern:

Be it known that I, EDWARD T. REDDING, a citizen of the United States, residing at Swissvale, in the county of Allegheny and

5 State of Pennsylvania, have invented certain new and useful Improvements in Apparatus for Making Flattened Expanded-Metal Reinforcement, of which the following is a specification.

10 My invention in general is in the nature of an improvement upon the Golding method of making expanded sheet metal, described in the Golding Patent No. 527,242 of October 9, 1894, and has for its primary object

15 to act upon and improve the Golding or similar expanded metal product, as distinguished from "deployed" metal which is adapted merely for use as lathing, so as to advantageously permit the employment of

20 the new structure in certain lines of reinforcement work where tensility and a perfect bond are big factors. It may be said that the improved structure is particularly adapted for use in connection with relatively

25 thin concrete slabs or tiles as an improved means of reinforcement designed to effect a material increase in the tensile strength of the same, to reduce the seasoning time heretofore considered necessary to season the

30 slab or tile before it could properly be used for building purposes, and to permit of the employment of a relatively thinner tile than hitherto obtainable. Another object of the

35 invention is the provision of novel means designed to provide and form a simple, highly flexible and economical reinforcing element singularly free from distortion or irregularity in contour, and embodying thinned strands and connecting webs whose upper 40 and lower surfaces respectively lie in an identic plane.

In the drawings, Figure 1 illustrates a piece of the aforesaid Golding expanded metal product;

45 Fig. 2 is a plan view of the rolling machine for turning over the strands and webs of the expanded metal and then straightening out the piece;

Fig. 3 represents a view of the new structure;

50 Figs. 4, 5 and 6 are enlarged contrasting views in perspective of similar portions of the old product, and intermediate stage in the process of the turning over of the webs and strands thereof, and the new structure;

Fig. 7 is a longitudinal sectional view of the machine in Fig. 2 and taken along the line VII—VII;

Fig. 8 represents a view illustrating diagrammatically the longitudinal directional travel of the metal through the machine during the turning over and flattening operation, the breaking up of any spiral formation of the metal piece which may be produced by the turning over and flattening operation, the rolling operation, and the final straightening out of the metal piece to obviate any tendency to bend that may be due to the rolling of the metal; and

Figs. 9, 10 and 11 represent slightly enlarged views of detail portions of the machine.

Figs. 1 and 4 of the drawings clearly indicate the structural characteristics of the Golding or similar expanded metal A, 75 wherein the bent strands 6 which constitute the boundaries of the diamond mesh, do not lie in the same horizontal plane. The expanded metal is manufactured from sheet steel and is worked cold. The sheet is 80 laid on the table of the cutting machine with one edge thereof projecting from the edge of the table a distance equal to the width of the strands 6 and a knife bar cuts the projecting metal by a shearing action so that the 85 strands are formed at regular intervals throughout the length of the sheet. The knives are so shaped that the metal is left uncut at a short distance from the end of the strand while the metal of the strand is forced 90 downward and the entire strand cold-drawn to form a half-diamond. The plane of the diamond is then approximately at right angles to the plane of the uncut sheet. The knife-bar is then moved in the direction of 95 the length of the sheet and the sheet is then projected over the cutting edge a distance equal to the width of the strand and when the bar next descends the uncut portion of metal where the strands of the first half-

100 diamond are joined now become the bottom of the loops forming the second row of half-diamonds. The knife-bar then returns to the original position and the third row of half-diamonds is formed, the strands being 105 everywhere parallel to the first row and joined to the strands of the second row by the continuous uncut portions or webs 7. This process is continued until the entire sheet is passed under the knife and the com- 110

plete piece of expanded metal has been finished.

These strands and webs have their greatest metal dimension (or width) running in a substantial vertical direction, and this vertical dimension is increased two-fold at the bridges or joint 7, resulting in a structure possessing such height and rigidity as to seriously impair the effectiveness of its employment with relatively thin slabs or tile, as frequently portions of it would project above the neutral axis of the tile and into or through the concrete of its underface, resulting in a fracture and failure of the tile when the latter was subjected to a normal stress. My invention is intended to overcome these objections producing as I do by my improved apparatus, a structure capable of acting as an efficient reinforcement for a very thin tile, and of imparting to such structures a measure of tensile strength heretofore unattained.

In carrying out my invention I subject the Golding or other similar expanded metal product, as distinguished from "deployed" metal lathing, to a bending pressure sufficient in degree to turn over and straighten or flatten the vertical strands 6 and webs 7 so that throughout the piece they assume an identic horizontal plane position, the strands and webs in the new and thin structure B being designated by the reference numerals 8 and 9 respectively.

The feeding of the rigid product A between superposed rolls, as 10, 10' and 11, 11', is the medium of pressure application I prefer to employ, the product being frictionally engaged with and supported during its passage through the rolls upon a traveling reciprocating plate member 12 disposed longitudinally of the frame 13 for movement in the pass of the rolls. The latter are adapted to rotate as a unit, the rotation being communicated to the plate 12 by means of the rack 14 formed on its under face and the pinion 15 preferably mounted centrally of the lower roll 10' in mesh with the rack. The rolls 10 and 10' are geared together, as are the rolls 11 and 11', by the upper gears 16 and 17 and lower gears 16' and 17', the former being meshed with a drive pinion 18 which has a drive shaft 19. The latter is connected with a source of power adapted to impart rotary movement to the rolls, and provided with suitable reversing mechanism adapted to intermittently reverse such rotation, this opposed directional rotation of the rolls being translated into reciprocatory movement of the plate member 12 toward and from the table 20 upon which the rigid product is designed to be initially positioned. The roll 11' is peripherally recessed centrally at 21 to permit the passage of the rack 14; and roller supports 22 are provided at spaced

intervals laterally of the rack to provide adequate terminal support to the plate member in its extreme positions.

Fig. 2 of the drawings illustrates the location of the plate member when in its extreme retracted position, and at a time when the flexible product has been produced and the member about to be advanced toward the table 20 to receive the next piece of rigid product to be acted upon. The latter is placed on the table with its forward marginal edge portion in close proximity to the pass of the front rolls and is pressed theretoward co-incident with the initial retraction of the plate member. The action of the rolls is to turn over all the strands and webs of the rigid piece in the same direction so that the webs will tend to straighten out without crimping or crushing adjacent terminal portions of the strands, or elongating the piece, as is clearly indicated in Fig. 6 of the drawings, the degree of flattening of the metal being determined by relative roll adjustment. It will be understood that the product is placed on the feeding table 20 at the outset so that the longer axes of the diamond openings take right-angular positions with reference to the pass of the rolls, and that the vertical dimension of the pass equals substantially the sum of the thickness of the plate member 12 and half the overall height of the rigid piece less a fractional part of the same.

However, I find in actual practice the piece after passing through the front rolls has a tendency to spiral, *i. e.*, it begins to roll up starting at one corner, and in order to break this up I provide any suitable means rearwardly of said rolls such as the metal bars 23 and 24, the former being inclined in a direction away from the pass of the rolls and the latter being arcuate in cross-section and placed just above the bar 23 whereby to provide a curved or offset passage 25 between them for the piece to pass through before it reaches the second or rear pair of rolls. These bars may be terminally associated together as shown in Figs. 9 and 10 and rigidly secured to the sides of the frame 13 by means of bolts 26. During its passage through the rear rolls the piece, which was distorted in a lateral direction by the bars 23 and 24, is then straightened out, and in order to prevent the finished product from curling up over the rear rolls, or rolling up upon itself, commencing with the front marginal edge portion, I provide suitable means such as the two plates 27 and 28 which are spaced apart to form a straight horizontal passage 29 for the product to pass through. The lower bar or plate 28 is located so as to just clear the upper face of the plate member 12, and has its ends 28a preferably associated with the ends 27a of the upper plate 27. Headed

bolts 30 are provided to rigidly secure the plates to the sides of the frame 13, as indicated in Fig. 11 of the drawings. After passing through the passage 29 the new product is straight, and is then in readiness for cutting into suitable lengths or sections, such as the section of tile reinforcement illustrated in Fig. 3.

The new structure B, by the practice of this method, takes on new qualities and lends itself to very effective employment in concrete roof tiles and similar relatively thin building slabs, and I have found by actual test that a tile so provided will withstand approximately 38 per cent. greater tension stress than a similar tile provided with the Golding metal product having in it substantially 8.5 per cent. more metal. One of its advantages resides in the fact that it may be readily located in proper position in the tile during the formation of the latter, that is, in a zone between its neutral axis and lower face which in the majority of instances may only provide a leeway expressed in terms of one or two sixteenths of an inch. Another advantage will be readily perceived by those skilled in the art to be present in the new structure, namely, by sacrificing a portion of the increase gained in tensile strength it is possible to effect a corresponding reduction in the number of days heretofore required to season a concrete tile prior to its release for use in building. A full purchase or hold is obtained in the concrete of the tile as the diamond openings are large and the sides and ends of the section B are closed. It will be obvious that a number of sections may be cut from the larger piece either before or after rolling, the latter preferred. The metal of the section may be 16 gage thickness but preferably thicker and the diamond-shaped openings substantially three inches in width, distinguishing from worked deployable metal of 24 gage and less having small openings of approximately three-eighths of an inch in width, and which is only adapted for use as lathing, and not as a structural reinforcement.

The method hereindescribed is made the subject matter of my divisional application No. 279,783 filed Feb. 28, 1919.

What I claim is:

1. In a machine of the character described, the combination of a frame, a pair of rolls mounted in said frame, a reciprocating carrier disposed in the pass of said rolls, and a straightening device carried in said frame adjacent the rolls.

2. In a machine for flattening and treating metal fabric, the combination of a frame, a plurality of rolls coöperating in said frame to flatten the fabric, a fabric carrier for said rolls, means for reciprocating the carrier in the pass of the rolls,

means carried by the frame for slidably supporting the carrier, and means positioned with reference to the rolls and said carrier for successively distorting and straightening out the flattened metal fabric. 70

3. In a machine for treating stretched strand Golding metallic fabric, the combination of a frame, rolls in said frame, a fabric carrier for said rolls movable in the pass of the rolls and coöperating with the latter to turn the strands and bridges, and means for straightening the fabric after its passage through the rolls. 75

4. In a machine for treating stretched strand metal fabric such as Golding fabric, 80 the combination of a flattening roll and a plate like member between which the fabric is introduced, said member being movable with the fabric and coöperating with the roll to turn the strands and bridges of the 85 fabric substantially into the original plane of the stock.

5. In a machine for treating stretched strand metal fabric such as Golding fabric, the combination of a flattening roll and 90 traveling means moving across said roll in the direction of the travel of the fabric and coextensive at least with the fabric in width, the fabric being introduced between said roll and said means which coöperate 95 to turn the strands and bridges substantially to the original plane of the stock.

6. In a machine for treating stretched strand metal fabric such as Golding fabric, the combination of a roll and traveling 100 means moving across said roll in the direction of the travel of the fabric and coextensive at least with the fabric in width, the fabric being introduced between said roll and said means, together with means bending 105 the fabric after it leaves the roll.

7. In a machine for treating metallic fabric, the combination of rolling means and means operating after the fabric leaves such rolling means to remove the bending given 110 to the fabric by the rolling means and giving a reverse bend to the fabric.

8. In a machine for treating metallic fabric, the combination of two rolling means, 115 a means intermediate said rolling means operating to bend the fabric reversely of its bent condition as it leaves the first rolling means, and means for straightening the fabric as it leaves the second rolling means.

9. In a machine for treating metallic fabric, the combination of compressing means between which the fabric is passed, and means causing the fabric as it leaves such means to travel in a tortuous path. 120

10. In a machine for flattening metallic 125 fabric to turn over the bridges and strands into substantially the original plane of the stock, the combination of a flattening member, and a traveling carrier moving relative to said member and operating as a com- 130

- pression member, the fabric being introduced between the flattening member and the traveling carrier so that the two co-operate to turn over the bridges and strands.
- 5 11. In a machine for flattening metallic fabric to turn the bridges and strands there-over into substantially the original plane of the stock, the combination of a plurality of rolls and a carrier movable through the 10 pass of the rolls and adapted to support the fabric across its width and coöperating with the rolls to turn over the bridges and strands.
12. In a machine for treating metallic fabric, the combination of a rotating compression member and a lineally traveling compressing member between which the fabric is introduced, said two members co-operating to turn over the strands and bridges of the fabric to a horizontal plane. 15 20

EDWARD T. REDDING.
